UNITED STATES PATENT OFFICE.

JOSEPH H. HUNTER, OF DETROIT, MICHIGAN.

NONSTRETCHABLE CORD.

1,405,591.

Specification of Letters Patent. Patented Feb. 7, 1922.

Application filed October 11, 1920. Serial No. 416,113.

To all whom it may concern:

Be it known that I, JOSEPH H. HUNTER, a citizen of the United States of America, residing at Detroit, in the county of Wayne and State of Michigan, have invented certain new and useful Improvements in Non-stretchable Cords, of which the following is a specification, reference being had therein to the accompanying drawings.

10 The invention relates to material used in the manufacture of flexible hangers and for other similar purposes, which is in the form of a flexible rope or heavy cord. In the present state of the art, this material is usually 15 formed of a stranded cord of suitable dimensions having a covering applied thereto, and in the manufacture of hangers the cord is cut into suitable lengths and provided at its ends with attachment devices secured thereto. It has been found that such material has 20 a great tendency to elongate after use, due both to the stretching of the material itself and the slipping of the engagement of the attachment means. To avoid such a result, 25 I have devised a construction comprising essentially a non-stretchable central core formed of a link chain, together with a surrounding body of flexible cushioning material for enlarging and retaining uniform 30 the diameter of the cord. This construction has not only the advantage of preventing elongation of the cord itself, but also provides a means of engagement with the fastening device, which will preclude any 35 slipping.

In the drawings:

Figure 1 is a longitudinal section through a portion of the cord, showing the construction thereof and the application of a fastening device thereto;

Figure 2 is an elevation of a robe hanger formed of the cord;

Figure 3 is a view similar to Figure 1 showing a modification.

45 A is a link chain of any suitable construction and of any desired material. This chain is covered with a body formed of spirally wound strands of flexible material such as cotton. The windings are preferably in 50 alternate layers B and C wound in reverse directions and the distribution of the strands is such that the irregularities in the diameter

of the chain are compensated for, retaining the body of uniform diameter. The spiral wrappings are secured by a fabric covering E, preferably of a spiral weave or braid. The outer surface may then be covered by any suitable ornamental material, if this is desired.

To form hangers of this material, it is 60 cut to the proper length and the ends of the sections have attached thereto fasteners F, which are preferably provided with prongs G or equivalent means for inserting through the wrappings and into engagement with 65 one or more of the chain links. Thus when complete, the device has all the flexibility of the rope hangers, but is practically non-stretchable.

With the construction shown in Figure 3, 70 instead of forming the body covering the chain of spirally wound layers, it is formed of longitudinally extending strands H, which are secured in position by the fabric covering E.

75 What I claim as my invention is:

1. A non-stretchable flexible material comprising a central core formed of a metallic link chain, a body surrounding said core formed of a plurality of spiral wrappings of 80 stranded material alternately wound in opposite directions, said wrappings enlarging and rendering substantially uniform the diameter of the body, and a fabric cover for said wrappings.

2. A non-stretchable flexible material for the forming of hangers, comprising a central core formed of a metallic link chain, a body surrounding said core formed of spiral wrappings of stranded material enlarging 90 and rendering uniform the diameter thereof, a fabric covering surrounding said wrappings, and a fastening device at the end having means for engaging one or more links of said chain to prevent displacement. 95

3. A non-stretchable flexible material comprising a central core formed of a metallic link chain, a body of cushioning material surrounding said chain and enlarging the diameter, and a covering for retaining said 100 body.

In testimony whereof I affix my signature.

JOSEPH H. HUNTER.
